INVENTOR.
August F. Bauer
BY
Warren A. House.
His ATTORNEY

UNITED STATES PATENT OFFICE.

AUGUST F. BAUER, OF KANSAS CITY, MISSOURI.

MEAT CHOPPER.

Application filed October 28, 1918. Serial No. 259,907.

To all whom it may concern:

Be it known that I, AUGUST F. BAUER, a citizen of the United States, residing at Kansas City, in the county of Jackson and 5 State of Missouri, have invented a certain new and useful Improvement in Meat Choppers, of which the following is a specification.

My invention relates to improvements in 10 meat choppers.

It relates particularly to the type of power choppers in which a screw is rotatable in a cylinder carrying at its discharge end a perforated plate through which the material to 15 be chopped is forced by a knife rotatably mounted at the forward end of the feed screw.

One of the objects of my invention is to provide a support for the forward end of 20 the feed screw which can be lubricated without liability of the lubricating material mixing with the chopped material.

A further object of my invention is to provide a support for the forward end of the 25 feed screw which will be subjected to a minimum of wear, and by which the knife will be retained in proper operative relationship to the perforated plate, and which will eliminate the usual chattering of the forward end 30 of the feed screw due to the wearing of an unlubricated bearing, government restrictions preventing the lubrication of bearings where the lubricating material is liable to mix with the chopped material.

35 My invention provides further other novel features which are hereinafter fully described and claimed.

In the accompanying drawing which illustrates the preferred embodiment of my in- 40 vention,

Fig. 1 is a side elevation of a meat chopper provided with my improvement.

Fig. 2 is an enlarged horizontal sectional view of the forward portion of the chopper.

45 Fig. 3 is a cross section on the line 3—3 of Fig. 2.

Fig. 4 is a cross section on the line 4—4 of Fig. 2.

Similar reference characters designate 50 similar parts in the different views.

1 designates the column or base of the chopper, 2 the cylinder, and 3 the feed screw, which is of the usual type, and which is provided in its forward end with an axial screw 55 threaded hole in which is fitted the inner end of a forwardly extending horizontal

axial shaft 4 having a squared portion 5 on which is removably fitted the usual knife 6.

The outer end of the cylinder 2 is screw threaded and has secured thereto a member 60 7, preferably a transversely divided internally screw threaded clamping ring 8 arranged to hold a perforated plate 9 against the outer side of the knife 6. A washer 10 may be inserted between the knife 6 and the 65 screw 3 on the shaft 4.

The ring 8 is preferably provided with two peripheral lugs 11 and 12, the latter having a threaded hole in which is fitted a screw 13 which is rotatably mounted in the 70 lug 11. By adjusting the screw 13, the ring 8 may be tightly clamped on the cylinder 2.

The ring 8 is provided with one or more forwardly extending arms 14 which are integral at their forward ends with a circular threaded portion 15 on which is fitted a screw threaded cap 16, which is adapted to press grease against the outer end of a bearing carried within the circular portion 15 and in which the outer end of the shaft 4 is 80 rotatably mounted. This bearing comprises, preferably two rings 17 and 18 mounted concentrically one within the other. The ring 17 is provided with two annular peripheral grooves in which are located balls 19 which 85 are also located in two grooves provided on the inner side of the outer bearing ring 18. The inner ring 17 encircles the shaft 4.

At the inner end of the bearing just described, a sealing means is provided for preventing grease or oil passing inwardly from the bearing on the shaft 4. Such sealing means consists, preferably, in a ring 20 of the same diameter as the ring 18, mounted on the shaft 4 in the circular portion 15, 95 and provided on its inner side with an annular groove in which is fitted packing material 21, such as felt or waste.

The shaft 4 extends through and is rotatable in a central hole provided in the per- 100 forated plate 9.

Grease is placed in the cap 16, and the latter is screwed onto the circular portion 15, so as to force the grease into the bearing and around the outer end of the shaft 4. 105 The ring 20 and packing material 21 prevents the grease from passing along the shaft 4 to a point where the grease could mix with the chopped material passing outwardly through the perforated plate 9. The 110 shaft 4 supports the outer end of the screw 3. By removing the ring 8, after loosening

the screw 13, the plate 9, knife 6, shaft 4 and feed screw 3 may be removed for the purpose of cleansing.

My invention provides a lubricated support for the outer end of the feed screw without liability of the lubricating material mixing with the chopped material, said support being located forward of and spaced apart from the point of discharge of the material, 10 such point being, as shown, at the forward side of the perforated plate 9.

I do not limit my invention to the structure shown and described, as modifications, within the scope of the appended claims, 15 may be made without departing from the spirit of my invention.

What I claim is:—

1. In a meat chopper, a chopper cylinder, a feed screw rotatable therein, a perforated 20 plate mounted transversely across the discharge end of said cylinder, the chopped material being discharged from the chopper at a point forward of said plate, a bearing member secured to the cylinder and having 25 an arm extending forwardly beyond the discharge end of the cylinder, said member having means for retaining said perforated plate in operative position, an axial shaft extending through said perforated plate and 30 having its inner end secured to and rotatable with the outer end of said screw, the outer end of the shaft being rotatably mounted in said bearing member at a point forward of and spaced apart from said point of discharge, and a knife mounted on and rotatable with said shaft intermediate the screw and said perforated plate and having 35 a bearing against the inner side of the latter, substantially as set forth.
- 40 2. In a meat chopper, a chopper cylinder, a feed screw rotatable therein, a perforated plate mounted transversely across the discharge end of said cylinder, the chopped material being discharged from the chopper at a point forward of said plate, an axial shaft 45 extending through said perforated plate and having its inner end secured to and rotatable with the outer end of said screw, a knife mounted on and rotatable with said shaft intermediate the screw and said perforated plate and having a bearing against the inner side of the latter, and means carried by said cylinder for retaining said perforated plate 50 in operative position and for rotatably supporting said shaft at a point forward of and spaced apart from said point of discharge, substantially as set forth.

3. In a meat chopper, a chopper cylinder, a feed screw rotatable therein, a perforated plate mounted transversely across the discharge end of said cylinder, the chopped material being discharged from the chopper at a point forward of said plate, an axial shaft 60 extending through said perforated plate and having its inner end secured to and rotatable with said screw, a knife mounted on and rotatable with said shaft and bearing against said perforated plate, and means carried by said cylinder for retaining said perforated plate in operative position and for rotatably 65 supporting the outer end of said shaft at a point forward of and spaced apart from said point of discharge, substantially as set forth.

4. In a meat chopper, a chopper cylinder, 75 having a threaded discharge end, a feed screw rotatable therein, a perforated plate mounted transversely across the discharge end of said cylinder, a shaft extending through said perforated plate and having its 80 inner end secured axially to and rotatable with said screw, a knife mounted on said shaft intermediate the screw and plate and bearing against the latter, a transversely divided threaded ring member fitted on the 85 threaded end of said cylinder and engaging and retaining said plate in its operative position, and adjustable means for contracting said ring member, so that it will clamp said cylinder, substantially as set forth.

5. In a meat chopper, a chopper cylinder having a threaded discharge end, a feed screw rotatable therein, a perforated plate mounted transversely across the discharge end of said cylinder, a shaft extending 95 through said perforated plate and having its inner end secured axially to and rotatable with said screw, a knife mounted on said shaft intermediate the screw and the plate and bearing against the latter, a transversely 100 divided threaded ring member fitted on the threaded end of said cylinder and engaging and retaining said plate in its operative position and having a forwardly extending arm a bearing carried by said arm forward of 105 and spaced apart from said plate and rotatably supporting the outer end of said shaft, and adjustable means for contracting said ring member so that it will clamp said cylinder, substantially as set forth.

In testimony whereof I have signed my name to this specification.

AUGUST F. BAUER
